ABSTRACT OF THE DISCLOSURE

This invention relates to a doorknob, wherein the knob is of cylindrical shape except for a finger groove interrupting the cylindrical knob surface on one side, preferably at right angles to the cylinder axis. The knob may be fixed to the door or may be rotatably mounted to operate a conventional latching mechanism. In the latter case the knob may be secured to any of the four faces of the conventional squared shaft, to vary the orientation of the finger groove.

This invention relates to a doorknob, intended to be grasped for the opening or closing of a door. Such knob may be fixedly secured to the door or alternatively may be rotationally mounted thereon for the actuation of a catch member for latching the door in its closed position. Hitherto, such a doorknob has usually had a narrow neck or stem with an enlarged head shaped for convenient grasping by the whole hand.

The present invention has for its object to provide an improved shape of doorknob, which, whilst having advantages for normal users, is especially advantageous for use by persons having injured or crippled hands, for whom the grasping of an ordinary doorknob presents difficulty.

The doorknob, according to the invention, is of cylindrical shape, except that it has a groove cut away on one side for the reception of a finger. The generators of the surface of the groove preferably all lie at right angles to the direction of the axis of the cylinder. The front face of the doorknob is preferably plane and at right angles to the axis of the cylinder.

Such a doorknob may be fixedly secured to the door, with its rear surface in contact either with the door surface or with the surface of a plate secured to the door.

Alternatively, the doorknob may be rotatably mounted on the door and secured to a shaft which actuates a catch member serving to latch the door in its closed position. Conveniently, the doorknob is detachably secured to a squared actuating shaft, for example by means of a grub screw, so that it can be secured thereto in any one of four positions giving different orientations of the groove in the knob. It is especially advantageous, when the doorknob is made of metal, to employ a washer of plastics material, in the form of a hollow cylinder with an externally projecting flange at one end, such washer being interposed between the doorknob and a metal member secured to the door, for the journaling both axially and radially of the knob in such member. Thus, the flange of the plastics washer may be interposed between the rear surface of the doorknob and the surface of a metal plate secured to the door, whilst the cylinder of such washer is interposed between the outer surface of a cylindrical projection on the knob and the cylindrical surface of a circular hole in such plate.

The invention may be carried into practice in various ways, but some convenient alternative practical constructions of doorknob according thereto are illustrated by way of example in the accompanying drawings, in which:

FIGS. 1 and 2 show one construction of fixed door knob respectively in plan and in front elevation,

2

FIGS. 3 and 4 show a second construction of fixed door-knob also respectively in plan and in front elevation,

FIG. 5 shows a construction of rotatable doorknob in plan, and

FIG. 6 illustrates the door latching mechanism actuated by the rotatable doorknob of FIG. 5.

In all these arrangements, the main body of the knob consists of a cylindrical metal block, with parallel flat ends at right angles to the axis of the block, having a groove cut away on one side. Such groove has a smoothly curved surface, with its generators parallel to the flat ends of the block, the dimensions of the groove being such as comfortably to receive a finger. Thus, in practice, the knob is grasped, not by the whole hand as in previously known doorknobs, but between the side of the forefinger in the groove and the thumb lightly pressed against the opposite side of the knob.

The various arrangements now to be described differ from one another mainly in the manner in which the main body of the knob, as above-described is mounted on the door. In some instances, the knob is fixedly secured to the door, as is often required for example for cupboard doors, whilst in other instances the knob is rotatably mounted for the operation of a catch member for latching the door in its closed position, as is usual for room doors. Usually, it will be preferred to employ a smaller size of knob, when the knob is fixedly secured to, say, a cupboard door, than when the knob is rotationally mounted for use for example on a room door. Since both sizes of knob are intended to be grasped by inserting a finger in the groove, the groove in the smaller size knob cannot be very much smaller than that in the larger size knob although there may be a large difference between the sizes of the knob itself. Thus, the relative proportions will be different in the two sizes of knob, and the small size knob will not be a true scale reduction of the larger size knob.

FIGS. 1 and 2 show a simple arrangement in which the knob is intended to be fixedly secured to the door, for example a cupboard door. For this purpose, the generally cylindrical main body A of the knob, with its finger groove A¹ on one side, has tapered and pointed screwthreaded shank B formed integrally with it or rigidly secured to it, such shank projecting from the rear flat face A² of the main body of the knob. The knob can thus be screwed directly into the door itself and, when so screwed in, the rear face of the knob will be in firm contact with the door surface.

In the arrangement of FIGS. 3 and 4, the knob, having a cylindrical main body C with finger groove C¹ on one side and with flat rear and front faces C² and C³, is again fixedly secured to the door D, but in this case a surface metal plate E is interposed between the knob and the door surface. In this arrangement it is preferred, first to secure the knob to the plate E, and then to secure the plate to the door surface. For this purpose, the rear face C² of the knob is bored with one or more screwthreaded holes, and a registering hole or holes are cut through the plate, so that the plate and the knob can be secured together in close contact by inserting a screw E¹ or screws through the plate E into the screwthreaded hole or holes in the knob C, the screw or each screw preferably having its head counter-sunk into the plate. The plate E is then secured to the door by means of screws E² passing through counter-sunk holes E³ in the plate.

In both the above arrangements care should be taken to orient the groove A¹ or C¹ in the desired position when secured to the door. Thus, if the knob is at normal level in front of the head or the upper part of the body of a normal sized person, the best orientation of the groove will be on one side of the knob, usually the

right-hand side, so that it can be comfortably grasped between the forefinger and the thumb of the right hand. If, however, the knob is at a higher level, it will be more convenient for the groove to lie across the top of the knob, so that a finger can be hooked into the groove for opening or closing the door. Similarly, for a low-level knob, the best orientation for the groove will be across the bottom of the knob.

In the third arrangement shown in FIGS. 5 and 6, the knob F is rotatably mounted for the operation of a catch member G housed in a lock casing H of the mortice type, such lock casing being secured in an opening cut from the edge of the door J between the two door surfaces. In this arrangement, there will usually be two door knobs F, one on each side of the door, and each with a side groove F¹ and with parallel plane rear and front surfaces F²F³, with a plate K secured to each door surface between the knob F and the door J.

The catch member G is mounted in the lock casing H so as to be movable longitudinally therein and is urged outwardly by a spring L so that it normally projects from the edge of the door into engagement in a recess cut in the door frame, such recess being covered by a metal plate M cut with a hole to receive the catch member. The projecting portion G¹ of the catch member G has its front surface parallel to the door surfaces and its rear surface at an angle thereto, for example 45 degrees, so that when the door is being closed from an open position, the oblique face of the catch member will engage with the fixed metal plate M on the door frame, which will push the catch member inwardly in the lock casing H against the action of the spring L, until the front surface of the catch member passes the edge of the hole in the fixed metal plate M, whereupon the catch member will spring outwardly into the recess and will latch the door in the closed position.

Within the lock casing, the catch member G has two projecting pins G²G³, with one of which G² one arm N¹ of a crank lever N¹N² engages. This crank lever is pivoted at N³ to the lock casing H, and its other arm N² is engaged by the spring L.

The crank lever N¹N² is also engaged by one of the arms O¹ of a pivoted lever O¹O², the other arm O² of which engages with the second catch member pin G³. At its pivot, the lever O¹O² has a boss O with a squared hole, through which passes a squared actuating shaft P, such shaft projecting from the lock casing H and passing through openings cut inwardly from the two surfaces of the door J, and also through circular holes in the two metal plates K secured to the two door surfaces.

Each door knob F has an integral cylindrical projection F⁴ from the centre of the rear face F² of the knob, such projection and also the main body of the knob having a squared hole bored in it for the reception of an end of the squared actuating shaft P. Mounted on such cylindrical projection F⁴, is a washer made of plastics material, for example nylon, consisting of a short hollow cylinder Q with an externally projecting flange Q¹ at one end. The internal surfaces of the cylinder Q of the washer fits closely around the cylindrical projection F⁴ on the door knob F, and the external surface thereof fits closely within the cylindrical surface of the hole in the metal plate K. The projecting flange Q¹ of the washer engages on one side with the rear face F² of the main body F of the door knob and on the other side with the outer surface of the metal plate K.

Each of the two door knobs F is firmly secured to the squared actuating shaft P by means of a grub screw P¹ engaging in a screwed hole in the door knob and pressing firmly against one of the four faces of the squared actuating shaft. It will be clear that there are thus four possible positions of the knob F on the shaft P, and the particular one of such positions used should be chosen to suit the best orientation of the groove in the knob, in accordance with the level at which the knob is located, in the manner above described.

In operation, with the door J latched in the closed position, the turning of either door knob F in either direction from its normal rest position will cause the catch member G to be withdrawn against the spring action and will thus unlatch the door, the catch member returning to its normal projecting position as soon as the door knob is released. The plastics washers QQ¹ afford much better sliding bearing surfaces with the metal surfaces, with which they engage, than the metal-to-metal bearing surfaces that would otherwise exist if such washers were not provided, especially if aluminium or an aluminium alloy is used for the metal, as is preferred.

This third arrangement may be modified, if desired by the use of a surface lock casing secured to one of the door surfaces, instead of a mortice lock casing. In such case, the door knob on the side of the door remote from the lock casing will be mounted on a metal plate on the door surface, with an intervening plastics washer, in the manner above described. On the other side of the door, the doorknob will be mounted on the exposed wall of the surface lock casing, with an intervening plastics washer, in a manner analogous to that described for the mounting of the doorknob on a metal plate.

It will be appreciated that the foregoing arrangements have been described by way of example only and may be modified within the scope of the invention in various ways. For example, it is not essential to the invention that the front surface of the doorknob should be plane and at right angles to the cylinder axis, although from an aesthetic viewpoint such arrangement is preferred.

What I claim as my invention and desire to secure by Letters Patent is:

1. A doorknob having a cylindrical surface, said surface being interrupted on one side only of a diametral plane extending along the axis of said surface by a groove having a size and position suited to receive a finger of a hand grasping said knob.

2. A doorknob as claimed in claim 1, in which the front surface of the knob consists of an uninterrupted plane surface at right angles to the axis of the cylindrical surface.

3. A doorknob as claimed in claim 1, in which the surface of the groove has parallel straight-line generators lying at right angles to the axis of the cylindrical surface.

4. A doorknob fitting comprising a doorknob as claimed in claim 1, a catch member for latching the door in its closed position, a rotatable shaft for actuating the catch member, and means for securing the doorknob to such shaft.

5. A doorknob as claimed in claim 3, including means for fixedly securing the knob to the door with the rear surface of the knob in contact with a surface carried by the door.

6. A doorknob fitting as claimed in claim 4 in which the knob is made of metal, including a metal member secured to the door, and a washer of plastics material in the form of a hollow cylinder with an externally projecting flange at one end, such washer being interposed between the knob and the said metal member and affording bearing surfaces for the journaling both axially and radially of the knob in the said metal member.

7. A doorknob fitting as claimed in claim 6 including a cylindrical projection on the knob, the cylinder of the plastics washer lying in bearing engagement between the outer surface of such cylindrical projection and the cylindrical surface of a circular hole in a metal plate constituting the said metal member secured to the door, the flange of the plastics washer lying in bearing engagement between the rear surface of the knob and the surface of such metal plate.

8. A doorknob fitting as claimed in claim 4, in which the rotatable shaft is of square cross-section, and the securing means permits detachment of the knob from such shaft, whereby the knob can be secured to the

shaft in any one of four positions giving different orientations of the groove in the knob.

9. A doorknob fitting as claimed in claim 8, in which the knob is made of metal, including a metal member secured to the door, and a washer of plastics material in the form of a hollow cylinder with an externally projecting flange at one end, such washer being interposed between the knob and the said metal member and affording bearing surfaces for the journalling both axially and radially of the knob in the said metal member.

10. A doorknob fitting as claimed in claim 9, including a cylindrical projection on the knob, the cylinder of the plastics washer lying in bearing engagement between the outer surface of such cylindrical projection and the cylindrical surface of a circular hole in a metal plate constituting the said metal member secured to the door, the flange of the plastics washer lying in bearing engagement between the rear surface of the knob and the surface of such metal plate.
